UNITED STATES PATENT OFFICE.

JOSEPH L. WELLS, OF PHILADELPHIA, PENNSYLVANIA, ASSIGNOR TO THE
WESTON & WELLS MANUFACTURING COMPANY, OF CAMDEN, N. J.

BREAST-FORM.

SPECIFICATION forming part of Letters Patent No. 358,711, dated March 1, 1887.

Application filed November 8, 1886. Serial No. 218,317. (No model.)

To all whom it may concern:

Be it known that I, JOSEPH L. WELLS, a citizen of the United States, residing at Philadelphia, in the county of Philadelphia and State of Pennsylvania, have invented certain new and useful Improvements in Breast-Pads or Dress-Forms; and I do hereby declare the following to be a full, clear, and exact description of the invention, reference being had to the accompanying drawing, which forms part of this specification, in which the figure is a perspective of a breast-pad or "dress-form" embodying my improvements.

My invention has reference to wire breast-pads or dress-forms, and has for its object to provide a cover therefor which shall serve as a "finish" for the article, protecting the person and garments of the wearer against contact with naked wire, such cover not, however, affecting the expansibility of the pads or forms under pressure or impact. Heretofore these pads or forms when made of braided wire have been finished around the edge by having stitched thereto a band of inelastic textile material. Owing to the inelasticity of this band it restrained the compressibility of the pad, so that when pressure was imposed upon the latter—such, for example, as would result from a tight-fitting waist or coat—the pad would yield to only a slight degree and the edge would bear rigidly against the surface on which it touched—to wit, the person of the wearer; and as the band was secured to only the lower or inner edge of the pad or form, and the rest of the latter was left unprovided with a special cover, it followed that the garment contacting with the wires of such pad would become soiled. To avoid these difficulties and to permit greater freedom of movement in the pad or form than heretofore, I provide the pads or forms with a covering of textile material which is knitted or braided or otherwise made of open-work character.

My invention accordingly consists in the combination, with a breast-pad or dress-form made of braided material, of a braided, knitted, or open-work elastic cover, substantially as hereinafter fully described.

Referring to the accompanying drawing, A

represents a pad or form, the body of which, B, 50 is composed of braided wire and consists of a tubular or cylindrical section, the ends of which are introverted or brought together and secured by a button or other fastening located on the inner or concave side of the pad or form. 55

D is the rim or edge of the pad or form, and is in use the part which rests against or nearest to the person of the wearer. When pressure is imposed upon the center, the rim or edge will expand or increase in diameter, if 60 not restrained by external influences, and it will also tend to curl up outwardly if sufficient pressure be produced on the center.

E is a covering of textile material—such as cotton, linen, silk, or wool—which is knitted, 65 braided, or otherwise made to have an open-work character, and is elastic, stretching readily when the rim or edge of the pad or form expands and contracting as the latter assumes its normal position or shape. This 70 cover is preferably made in the first instance in the form of a tube or cylinder, similar in shape to that of which the braided-wire body is composed, and is applied to said body by slipping it on over the latter, turning one of 75 its ends into the cavity or recess of the latter, and then securing both ends together at the center by stitching or other suitable form of fastening. The covering is thus both on the inner and outer or concave and convex sides of 80 the pad or form, and may be said to form a lining as well as a covering. It thus protects the person and garments of the wearer from contact with naked wire, rendering the article more comfortable and cleanly, yet does 85 not interfere with the easy yielding of the pad or form under compression or produce the rigidity or discomfort incident to pads having edges bound with inelastic fabric.

My invention is not necessarily confined to 90 braided-wire pads or forms, as the described cover may be applied to pads or forms of other construction or different material; but I prefer to use braided wire, as there is no other construction or material with which I am acquainted which will produce a pad or form having the desirable properties of one made of 95 braided wire.

What I claim as my invention is—

The combination, with the body of a breast-
pad or dress-form composed of braided mate-
rial, of a covering applied thereto, substan-
tially as described, said covering consist-
ing of a knitted, braided, or open-work elastic
textile material, substantially as shown and
set forth.

In testimony that I claim the foregoing I
have hereunto set my hand this 28th day of 10
October, 1886.

JOSEPH L. WELLS.
